(57) **CLAIM**

The ornamental design for an egg scale, as described and shown.

DESCRIPTION

FIG. 1 is a perspective view of the egg scale of the invention;

FIG. 2 is a front elevational view of the egg scale of FIG. 1;

FIG. 3 is a rear elevational view of the egg scale of FIG. 1;

FIG. 4 is left side elevational view of the egg scale of FIG. 1;

FIG. 5 is right side elevational view of the egg scale of FIG. 1;

FIG. 6 is top plan view of the egg scale of FIG. 1;

FIG. 7 is bottom plan view of the egg scale of FIG. 1;

FIG. 8 is a perspective view of a second embodiment of the egg scale of FIG. 1., the only difference being the text has been removed; and,

FIG. 9 is front elevational view of the egg scale of FIG. 8.
